(57) **CLAIM**

The ornamental design for an end cap for a ladder, as shown
and described.

DESCRIPTION

FIG. 1 is a perspective view illustrating a first embodiment
of our new and ornamental design for an end cap for a
ladder;

FIG. 2 is a left-side view illustrating the new and ornamental
design for the end cap for a ladder of FIG. 1;

FIG. 3 is a right-side view illustrating the new and ornamental
design for the end cap for a ladder of FIG. 1;

FIG. 4 is a front view illustrating the new and ornamental
design for the end cap for a ladder of FIG. 1;

FIG. 5 is a back view illustrating the new and ornamental
design for the end cap for a ladder of FIG. 1;

FIG. 6 is a top view illustrating the new and ornamental
design for the end cap for a ladder of FIG. 1;

FIG. 7 is a bottom view illustrating the new and ornamental
design for the end cap for a ladder of FIG. 1;

FIG. 8 is a perspective view illustrating a second embodiment
of the new and ornamental design for the end cap for
a ladder;

FIG. 9 is a top view illustrating the new and ornamental
design for the end cap for a ladder of FIG. 8;

FIG. 10 is a back view illustrating the new and ornamental
design for the end cap for a ladder of FIG. 8;

FIG. 11 is a left-side view illustrating the new and ornamental
design for the end cap for a ladder of FIG. 8;

FIG. 12 is a front view illustrating the new and ornamental
design for the end cap for a ladder of FIG. 8;

FIG. 13 is a bottom view illustrating the new and ornamental
design for the end cap for a ladder of FIG. 8;

FIG. 14 is a right-side view illustrating the new and ornamental
design for the end cap for a ladder of FIG. 8;

FIG. 15 is a perspective view illustrating a third embodiment
of the new and ornamental design for the end cap for a
ladder;

FIG. 16 is a top view illustrating the new and ornamental
design for the end cap for a ladder of FIG. 15;

FIG. 17 is a back view illustrating the new and ornamental
design for the end cap for a ladder of FIG. 15;

FIG. 18 is a left-side view illustrating the new and ornamental
design for the end cap for a ladder of FIG. 15;

FIG. 19 is a front view illustrating the new and ornamental
design for the end cap for a ladder of FIG. 15;

(Continued)

FIG. 20 is a bottom view illustrating the new and ornamental design for the end cap for a ladder of FIG. 15; and, FIG. 21 is a right-side view illustrating the new and ornamental design for the end cap for a ladder of FIG. 15. The broken lines shown in the figures are for the purpose of illustrating environment and form no part of the claimed design.
